UNITED STATES PATENT OFFICE.

WILLARD E. HULL, OF WATERTOWN, CONNECTICUT, ASSIGNOR OF ONE-HALF
TO JEAN JACQUES, OF SAME PLACE.

BANDAGE.

SPECIFICATION forming part of Letters Patent No. 236,033, dated December 28, 1880.
Application filed February 27, 1880.

To all whom it may concern:

Be it known that I, WILLARD E. HULL, of Watertown, in the county of Litchfield and State of Connecticut, have invented a new Improvement in Bandages; and I do hereby declare the following to be a full, clear, and exact description of the same.

This invention relates to an improvement in bandages for surgical and similar purposes, the object being to construct a bandage which will adhere to itself when two surfaces are brought together, but will not adhere to the part around which it is placed; and it consists in the bandage hereinafter described, and particularly defined in the claim.

I first take a strip of fabric of the required width for the bandage, or it may be a wider strip, to be subsequently cut into bandage width. I prepare by grinding a composition of rubber, litharge, and sulphur, in equal proportions, by weight, reducing it, by naphtha or equivalent solvent, to a consistency to readily strike into the fabric, then spread it upon the fabric in a spreading-machine, and when dry, or after standing for a short time, the bandage is complete. If the compound is on a broad fabric I cut it into strips of the width required for bandages and roll it, introducing a strip of paper of corresponding width between the meeting surfaces.

The bandage thus prepared will adhere to itself whenever two surfaces are brought together—as, for instance, in winding around a limb as it is brought around the first time, and lapped onto the end, it securely attaches itself thereto, then may be turned into another direction, and wound at another point, and secured in like manner. The direction of the bandage may be turned at any time by simply

bringing the parts together to secure them at 40 the point of turning, but it will not adhere to the skin. It dispenses with the use of pins, and enables winding an open bandage, and insures its retention upon the part where it is wound.

To medicate this bandage I take equal parts of the following herbs: Sassafras, elder-bark, rosemary-leaves, and arnica-leaves, and steep them to make a strong solution, or take extracts of the same in equal parts. After the 50 cloth has been prepared as above described immerse it in the solution and dry; or the oils may be used with alcohol and mixed with the coating before it is spread upon the fabric, using about ten to fifteen per cent., in weight, 55 of the medicating compound to the bandage composition.

To perfume the bandage to remove any offensive odor which might come from the coating, I use oil of lavender and bergamot cut 60 with alcohol, which may be introduced into the composition before spreading, or applied to the fabric after coating.

I do not broadly claim an india-rubber bandage; neither do I claim, broadly, a mixture of 65 rubber, litharge, and sulphur as a composition; neither do I claim a rubber cloth spread with medical substances.

I claim—

A bandage consisting of a strip of fabric 70 spread or coated with a composition or mixture of rubber, litharge, sulphur, sassafras, elder, rosemary, and arnica, substantially as described.

WILLARD E. HULL.
